UNITED STATES PATENT OFFICE

CHARLES HUGH DUFFY, OF MIAMI, FLORIDA

SHIELD ATTACHMENT FOR BINOCULARS

Application filed March 2, 1928. Serial No. 258,618.

This invention relates to a shield attachment for the eye-pieces of binoculars.

It has been found in attempting to make binocular observations from aircraft, that the high relative wind causes tears to accumulate in the eyes of the observer which dim the vision. An eye shield therefore becomes almost a necessity in observations of this character.

10 In many types of commercial binoculars, the lateral distance between the lenses of the eye-pieces may be adjusted to suit the spacing of the eyes of different persons, and the eye-pieces may also be independently focused. An 15 object of this invention is to apply an eye-shield to binoculars of this type, of such construction as to permit the independent focusing and lateral adjustment above mentioned without disturbing the eye-shield.

20 According to my invention the attachment is so constructed and arranged that it may be readily attached to or detached from the eye-pieces of the binoculars. It comprises a 25 pair of substantially semi-circular frame members made so as to conform to the contour of the eye-pieces of the binoculars, each semi-circular member having a projecting hook-shaped lug adapted to engage the annular flange of the eye-pieces of the binoculars in such manner as to permit the rotation 30 of the said eye-pieces within and in relation to said frame members. The eye-shields proper, attached to the semi-circular frame members are composed of suitable flexible material, such as rubber, leather or the like.

35 The two semi-circular frame members are connected together by a telescopic yoke piece comprising a cylindrical element connected to one of the frame members which receives a piston head connected by a piston rod to the other frame member. Between the piston head and one end of the cylindrical element a spring is disposed so as to tend to force the frame members toward each other.

40 The invention is described with more particularity in the following specification with reference to the accompanying drawings.

In the drawings:

45 Figure 1 is a plan view of a commercial

type of binoculars having my invention applied thereto,

Figure 2 is an end view of the eye-piece end of the binoculars with the attachment in operative position; and

55 Figure 3 is an end view of the shield attachment showing the cylindrical element in longitudinal section.

The numeral 10 designates binoculars of a commercial type, laterally adjustable about a central shaft 11 to vary the distance between the eye-pieces. For adjusting the focus of the eye-piece lenses the eye-pieces 12, having outwardly flared flanges 13, may be rotated in order to produce longitudinal inward or outward movements thereof, in accordance with common practice.

60 According to my invention substantially semi-circular frame members 14, 15 are provided with arcuate recesses 16 adapted to engage the cylindrical shell of the eye-pieces 12 at the base of the outwardly flared flanges 13. The inner face 17 of each frame member is inclined outwardly at approximately the same angle as the corresponding flange 13. A 65 hook-shaped lug 18 projecting from each frame member at the outer diameter of its face 17 is adapted to engage over the outer rim of the flanges 13 so as to move the frame members laterally with the eye-pieces and 70 permit independent rotation of said eye-pieces. At the outer diameter of the inclined face 17 each frame member is provided with outwardly bent spaced flanges 19 and 20. The former is of continuous arcuate shape while the latter includes a number of spaced, apertured bosses 21. The eye shield proper 22 composed of suitable flexible material, such as rubber has one edge 75 thereof inserted between the spaced flanges 19, 20 and is secured thereto by rivets 23 which pass through flange 19, the shield 22 and bosses 21.

80 The frame member 15 has a rod 24, and the frame member 14 has a rod 25 extending 85 tangentially therefrom in such directions that the rods 24 and 25 extend toward each other. The rod 24 terminates in a hollow cylindrical element 26, one end of which is adapted to be partially closed by an aper-

tured, detachable cap 27. On the other hand, the rod 25 terminates in a piston head 28' which is slidably mounted in the cylinder 26, the rod 25 passing through the aperture in end cap 27. A coil spring 28 embracing the piston rod 25 and compressed between the piston head 28' and end cap 27 allows lateral adjustment of the frame members and tends to hold the shields 22 firmly 10 against the face of the observer so as to protect the eyes from air currents, swiftly traveling dust and the like.

In operation, the attachment is placed in position by engaging the hook-shaped lugs 18 over the rims of the eye-piece flanges 13. The spring 28 yields to permit this operation as well as the lateral adjustment of the eye-pieces to suit the eyes of the observer. The spring being under compression acts in conjunction with arcuate recesses 16 and lugs 18 to hold the attachment firmly in position with relation to the eye-pieces. The latter, however, may be rotated for focusing, as the hook-shaped lugs do not engage the flanges 13 with sufficient tightness to interfere with this movement.

I claim:

A readily detachable eye-shield attachment for binoculars, including a pair of arcuate frame members shaped to directly engage the rotatable eye-pieces of binoculars, eye-shields mounted on said frame members, each of said arcuate frame members including an outwardly inclined portion and a lug, 35 between which outwardly inclined portion and lug a rotatable eye-piece of the binoculars is received, means for connecting the arcuate frame members together, said means including an extensible and contractable mechanism for resiliently drawing the frame members into operative engagement with the rotatable eye-pieces of the binoculars.

In testimony whereof I affix my signature.

CHARLES HUGH DUFFY.
